UNITED STATES PATENT OFFICE.

CARL H. BISSELL, OF SYRACUSE, NEW YORK, ASSIGNOR TO CROUSE-HINDS COMPANY, OF SYRACUSE, NEW YORK, A CORPORATION OF NEW YORK.

CAP FOR CONDUIT OUTLET-BOXES.

1,391,524.

Specification of Letters Patent. Patented Sept. 20, 1921.

Application filed September 3, 1919. Serial No. 321,302.

To all whom it may concern:

Be it known that I, CARL H. BISSELL, a citizen of the United States, and a resident of Syracuse, in the county of Onondaga and 5 State of New York, have invented a certain new and useful Cap for Conduit Outlet-Boxes, of which the following is a specification.

This invention has for its object a cap for 10 conduit outlet boxes, which house rotary snap switches, which cap is provided with a switch operating member for coacting with the button of the snap switch, and further has for its object, a particularly simple and 15 efficient construction of such operating member, whereby the indicator thereon showing whether the switch is on or off, can be adjusted to match or correspond with the position of the "on and off" indicating means 20 of the switch housed and concealed within the outlet box and cap.

The invention consists in the novel features and in the combinations and constructions hereinafter set forth and claimed.

25 In describing this invention, reference is had to the accompanying drawings, in which like characters designate corresponding parts in all the views.

Figures 1 and 2 are respectively a plan 30 and a vertical sectional view of a conduit outlet box and cap embodying my invention.

Fig. 3 is a plan view of the box, the cap being removed.

Fig. 4 is an enlarged sectional view 35 through the switch operating member.

Figs. 5 and 6 are opposing end views of the handle element and switch button engaging element.

Fig. 7 is a sectional view, taken on the 40 plane of line 7—7, Fig. 2.

Fig. 8 is a plan view of one form of snap switch.

1 designates a conduit outlet box, which 45 may be of any suitable form, size and construction.

2 a rotary switch having its base mounted on the bridge 3 located in the box and extending diametrically across the same, the switch having the usual non-circular rotary 50 operating button 4, and the usual indicator 5 showing the position of the switch, that is, whether it is "on or off."

6 designates the cap of the outlet box, the cap being secured to the base in any 55 suitable manner, as by screws 7. A suitable

gasket 8 is interposed between the opposing faces of the cap and base to make the entire housing weather tight.

The cap 6 is provided with a switch operating member comprising a handle, a switch button engaging element and a motion transmitting element between the handle and the button engaging element, the handle being adjustable relatively to the motion transmitting element, one of which is shiftable 60 or adjustable relatively to the other, means for holding said elements in their adjusted relation, and means for preventing retrograde movement of the operating member.

10 designates the switch operating member which is rotatably mounted in the cap.

11 is the motion transmitting element which is in the form of a shank journaled in a bearing in the top of the cap 6. 12 is the handle mounted on the shank. 13 is the 75 switch button engaging element here shown as in the form of a fork or non-circular socket adapted to receive the non-circular button 4 of the snap switch, the elements 11 and 13 having opposing clutch faces which 80 are here shown as provided with annular flanges or disks 14 and 15 mounted on the elements 11 and 13 and spaced apart and having clutch rings or raised corrugations 15 or 16 on their opposing faces, which rings 85 normally engage each other and hold the parts from relative rotary movement.

The elements 11 and 12 are clamped together in order to hold their clutch faces in engagement by suitable means here shown 90 as a clamping member or screw 17 extending axially through the element 11 and threading into the switch button engaging member 13. The head of the screw is located at the outer end of the motion transmitting element where it is accessible from the outside of the cap. Retrograde movement of the operating member 10 is prevented in order that the said member cannot be turned backwardly far enough to unscrew the switch button 4, by suitable means as a series of ratchet teeth 18 provided on the disk 14 and a pawl 19 carried by the cap and coacting with the ratchet teeth.

These ratchet teeth 18 are so spaced apart 105 as to engage with the pawl when the switch button reaches an "on or off" position. Said ratchet teeth are also provided on the disk 14 on the motion transmitting element 11, in order to permit the element or shank 110

- 11 to be turned backwardly relatively to the socket engaging member to engage one of the four ratchet teeth 18 with the pawl 19 before the screw 17 is tightened.
- 5 The handle 12 is mounted on the outer end of the shank 11 and adjustable about the same to position the indicator 20 therein to match or correspond with the "on and off" positions of the indicator of the switch.
- 10 Said handle is held in its adjusted position by a set screw 21.
- The bridge 3 is shown as being provided with downturned ends 22 formed with feet 23 which rest upon lugs 24 provided in the box, these feet having laterally extending open ended slots 25 which extend in opposite directions relatively to each other, the slots receiving screws 26 which thread into the lugs 24. The intermediate part of the 15 bridge is formed with a plurality of pairs of holes 27, the members of any one pair of which are spaced apart the proper distance to receive the attaching screws 28 of a standard make of switch, it being understood that 20 these screws are located different distances apart in different makes of switches.

In operation, the switch is mounted in the box and the position of the indicator noted, that is, it is noted whether the switch is "on" 30 or off." The cap is then placed in position with the switch button receiving element 13 engaging or receiving the switch button 4 of the switch.

When the cap is attached in position by 35 means of the screws 7, the indicator 20 on the handle 12 may point to the word "On" on the cap, while the indicator on the switch may indicate "off," or the indicator 19 may occupy a position between the words "On" 40 and "Off" on the cap. Therefore, in order to properly position the handle, so that it also indicates "off" to match or correspond to the position of the indicator on the switch, the screw 17 is loosened sufficiently to permit the motion transmitting element 11 to be turned so that one of the teeth 18 abuts against the pawl 19 and then the handle 12 is adjusted so that its indicator 20 points to the same word, that the indicator 50 of the switch showed before the cap was applied.

This device is particularly advantageous in that it provides a water and weather tight housing for snap switches and a particularly simple and efficient means for operating the snap switches from the outside of the housing.

What I claim is:

1. A cap for conduit outlet boxes having 60 a switch operating member associated therewith comprising a handle, a rotary switch button engaging element and a motion transmitting element between the handle and the former element, one element being 65 shiftable relatively to the other, and the

handle being shiftable relatively to the latter element and means for normally holding said elements from shifting movement relatively to each other, substantially as and for the purpose described.

2. A cap for conduit outlet boxes having 70 a switch operating member associated therewith comprising a handle, a rotary switch button engaging element and a motion transmitting element between the handle and the former element, one element being shiftable relatively to the other, and the handle being shiftable relatively to the latter element, means for normally holding said elements from shifting movement relatively to each other, and means for preventing retrograde movement of the motion transmitting element, substantially as and for the purpose specified.

3. A cap for conduit outlet boxes having 80 a switch operating member associated therewith comprising two rotatable elements arranged in axial alinement, one element being journaled in the cap, a handle mounted on said element, and adjustable about the axis of the same, and one element having an adjusting movement relatively to the other about its axis and means for holding said elements in their adjusted position, substantially as and for the purpose set forth.

4. A cap for conduit outlet boxes having a 90 switch operating member associated therewith comprising two rotatable elements arranged in axial alinement, one element being journaled in the cap, a handle mounted on said element, and adjustable about the axis of the same, and one element having an adjusting movement relatively to the other about its axis, means for holding said elements in their adjusted position, and means 100 for preventing retrograde movement of the adjustable element, substantially as and for the purpose described.

5. A cap for conduit outlet boxes having a 105 switch operating member associated therewith comprising a rotatable element journaled in the cap, a handle mounted on said element, and a rotatable switch button engaging element located in the cap and arranged in axial alinement with the former element, 110 said elements having friction faces at their opposing ends and being adjustable relatively to each other about the axis of the handle and the button engaging element, and means for clamping the elements 115 together in their adjusted position, substantially as and for the purpose specified.

6. A cap for conduit outlet boxes having a 120 switch operating member associated therewith comprising a rotatable element journaled in the cap, a handle mounted on said element and a rotatable switch button engaging element located in the cap and arranged in axial alinement with the former element, 125 said elements having friction faces at their 130

opposing ends and means for clamping the elements together, said means extending lengthwise of the former elements through the outer end of the same, substantially as 5 and for the purpose set forth.

7. A cap for conduit outlet boxes having a switch operating member associated therewith comprising a rotatable element journaled in the cap, a handle mounted on said 10 element, and a rotatable switch button engaging element located in the cap and arranged in axial alinement with the former element, said elements having friction faces at their opposing ends, means for clamping 15 the elements together, the handle being adjustable about the former element, and means for preventing retrograde movement of the former element, substantially as and for the purpose described.

20 8. A cap for conduit outlet boxes having a switch operating member associated therewith comprising a rotatable element journaled in the cap and a rotatable switch button engaging element formed with a non-circular socket for receiving the button of a 25 rotary switch, the former element being adjustable about its axis relatively to the latter element, means for holding the handle element in its adjusted position relatively to 30 the switch button engaging element, a handle mounted on the former element and adjustable about the same, and means for preventing retrograde movement of the former element, substantially as and for the purpose 35 specified.

9. A cap for conduit outlet boxes having a switch operating member associated therewith comprising a rotatable element and a rotatable switch button engaging element arranged in axial alinement and having clutch 40 faces at their opposing ends, means for clamping the elements together, a handle mounted on the outer end of the former element and adjustable about the axis of the 45 same, substantially as and for the purpose set forth.

10. A cap for conduit outlet boxes having a switch operating member associated therewith comprising a rotary element journaled 50 in the cap and a rotary switch button engaging element located in the cap and having means for engaging the button of a rotary switch, said elements having clutch faces on the opposing ends, and a clamping member 55 extending lengthwise of the former element and threading into the switch button engaging element, a handle mounted on the outer end of the former element and means for preventing retrograde movement of the

former element, substantially as and for the 60 purpose described.

11. A cap for conduit outlet boxes having a switch operating member associated therewith comprising a rotary element journaled 65 in the cap and a switch button engaging element located within the cap and arranged in axial alinement with the former element, said elements being provided at their opposing ends with annular spaced apart flanges having corrugated clutch surfaces on their 70 opposing faces for engaging each other, and means operable from the outer end of the former element for clamping said elements together and engaging said clutch faces, substantially as and for the purpose specified. 75

12. A switch operating member comprising a handle and a rotary motion transmitting element on which the handle is mounted, a rotary switch button engaging element, one of said elements being shiftable about 80 its axis relatively to the other and the handle being shiftable relatively to the motion transmitting element, and means for holding the motion transmitting element and the button engaging element in their adjusted 85 position, substantially as and for the purpose described.

13. A switch operating member comprising a handle, a motion transmitting element, a rotary switch engaging element, one 90 of said elements being shiftable relatively to the other about its axis, the handle being shiftable relatively to the motion transmitting element, means for normally holding said elements from shifting movement relatively to each other, and means for preventing retrograde movement of the motion transmitting element, substantially as and for the purpose specified. 95

14. A switch operating member comprising a rotary motion transmitting element, a rotary switch button engaging element having means for engaging the button of a rotary switch, said elements having clutch faces on their opposing ends, a clamping 100 member extending lengthwise of the former element and threading into the switch button engaging element, a handle mounted on the outer end of the motion transmitting element, and means for preventing retrograde 110 movement of the motion transmitting element, substantially as and for the purpose described.

In testimony whereof, I have hereunto signed my name, at Syracuse, in the county 115 of Onondaga, and State of New York, this 22nd day of August, 1919.

CARL H. BISSELL.
